BOOM CONVEYOR APPARATUS

Henry W. Hapman, Detroit, Mich., assignor of forty per cent to Hannah Jane Hapman, Detroit, Mich.

Application March 31, 1950, Serial No. 153,223

11 Claims. (Cl. 214—21)

This invention relates to material-feeding apparatus and, in particular, to coke oven feeding apparatus.

Hitherto, coke ovens, which are very long and narrow, have been mounted side by side in batteries and have been of very heavy construction in order to support rails on their roofs which in turn carry coal cars for dumping coal into the top portions of the ovens. This means of delivering coal to the ovens causes the coal to pile up in approximately conical heaps on the floor of the oven. In order to level off these piles of coal, coke manufacturers have hitherto used a so-called coke bar which is inserted through an opening in the front of the oven and pushed back and forth. In so doing, however, the coke bar usually pulls some coal out of the oven through the front opening, this spilled coal interfering with the operations and requiring additional labor to recover it or additional apparatus to return it to the interior of the oven. Since the charge for each oven ordinarily amounts to 15 tons of coal, the roof of the oven and the tracks, cars and structural steel at the top of the oven must be made very strong, thereby resulting in expensive installation. Moreover, the coke bar cannot be operated while dumping is taking place, hence its use consumes time and slows up the operation of the oven.

The present invention provides a self-contained car-mounted hopper and elongated boom conveyor which is filled with coal from the usual elevator at the end of the battery of ovens and which is then rolled on its supporting car to the oven which is to be charged with its approximately fifteen tons of coal. The lower car or longitudinal car is then halted and the upper car or transverse car carrying the conveying apparatus is then moved laterally to cause the conveyor on the boom to move from the front to the rear of the oven and back again, depositing half the entire charge of coal on its forward run and the other half on its return run in a smooth even-topped charge without any necessity for leveling it off. The boom conveyor is so constructed and arranged to withstand the oven temperature of around 1400° F. and goes into the combustion space at the top of the oven. The present invention fills the lower half of the oven going in and the upper half coming out, and requires no coke bar. It also eliminates the necessity for the unusually strong oven construction hitherto required in order to carry the weight of the coal cars, rails and supporting structure on top of the ovens in prior oven installations.

One object of this invention is therefore to provide a coke oven feeding apparatus which will completely fill a coke oven with a measured charge of coal through the front wall of the oven in a smooth level-topped heap without peaks which hitherto have had to be levelled off and consequently without requiring a coke bar for doing so, or a heavy roof construction for supporting the coal supply cars.

Another object is to provide a coke oven feeding apparatus of the foregoing character having an elongated boom conveyor adapted to be moved into and out of the

2

oven and to transfer a measured charge of coal from a self-contained hopper to the interior of the oven, depositing part of the charge while moving into the oven and the other part of the charge while moving out of the oven, thereby charging the oven to its full extent in the minimum time without spilling any of the coal out the front of the oven, as occurred with the coke bars hitherto used for leveling off the piles of coal deposited by coal supply cars through the top of the oven.

Another object is to provide a coke oven feeding apparatus of the foregoing character which is constructed and arranged of heat-resisting materials so as to withstand the high temperatures occurring in such ovens while charging such ovens.

Another object is to provide a coke oven feeding apparatus of the foregoing character which will dispense with and eliminate the heavy roof construction and the overhead rails, supporting structure and coal supply cars hitherto required for charging coke ovens with coal as well as to eliminate the coke bar and its supporting apparatus hitherto required for leveling off the piles of coal deposited by such prior charging apparatus.

Another object is to provide a coke oven feeding apparatus of the foregoing character wherein the endless flight conveyor used therein is provided with specially arranged shear pins so positioned as to give way and permit the flight or flights to fold backward along the chain in the event the conveyor encounters a lump or body of foreign material which would otherwise break the conveyor, thereby enabling the conveyor to keep moving until it can be withdrawn from the oven.

Another object is to provide a coke oven feeding apparatus of the foregoing character, wherein the chain of the endless flight conveyor of the apparatus and its supporting pulleys or sprockets are so constructed and arranged as to set up a whipping action which dislodges particles of coal that would otherwise tend to adhere to the chain and flights.

Another object is to provide a coke oven feeding apparatus of the foregoing character wherein the quantity of coal fed by the conveyor is adjustable by means of a regulating device located adjacent the supply hopper and under the control of the operator.

Another object is to provide a boom conveyor apparatus for delivering materials from a supply point to a delivery point remote from the supply point, regardless of possible obstructions between the two points over which the boom may extend, the boom being self-sustaining without the necessity of overhead braces, supports or suspensions, thereby enabling vehicles on different tracks or roadways, or vessels in different rows side by side on a waterway to be filled one by one without the necessity of disturbing those intervening between the two points, the conveyor being movable back and forth to variously position the outlet of the apparatus.

Another object is to provide a boom conveyor apparatus as set forth in the preceding objects wherein the boom is of tubular construction which not only renders it a strong elongated structure but also enables it to serve as a conduit structure for conveying the material from the supply point to the delivery point as well as carrying the endless conveyor back from the delivery point to the supply point.

In the drawings:

Figure 1 is a side elevation of a coke oven feeding apparatus, according to one form of the invention, with a portion of the lower car omitted and the coke oven being shown diagrammatically in dotted lines;

Figure 2 is a side elevation, partly in section, of the portion of the apparatus located at the rearward end of the endless conveyor;

Figure 3 is a vertical cross-section taken along the line 3—3 in Figure 2;

Figure 4 is a horizontal longitudinal section taken along the line 4—4 in Figure 3;

Figure 5 is a top plan view of the forward end of the apparatus partly broken away to show the endless flight conveyor;

Figure 6 is a longitudinal section taken along the line 6—6 in Figure 5;

Figure 7 is a right-hand end elevation of the portion of the apparatus shown in Figure 5;

Figure 8 is a vertical section through the conveyor chain supporting pulley taken along the line 8—8 in Figure 6; and

Figure 9 is a vertical section through one of the conveyor flight shear pins taken along the line 9—9 in Figure 6.

Referring to the drawings in detail, Figure 1 shows a side elevation of a boom conveyor apparatus, generally designated 10, according to one form of the invention, as applied to the feeding of coal to a coke oven. The boom conveyor apparatus 10 consists generally of lower supporting rails 11 carrying a lower car 12 on which are mounted upper supporting rails 13 transverse to the lower supporting rails 11 and carrying the upper car 14 which supports the boom conveyor unit or coke oven feeding unit, generally designated 15. The coke oven, one of which is shown in dotted lines and generally designated 16 in Figure 1, has top and bottom walls 17 and 18 and front and rear walls 19 and 20, the front wall 19 having an opening 21 therein closed by sliding or swinging doors 23 giving access to the combustion space 22 at the top of the oven 16. The rear wall 20 is also removable to enable the finished coke to be pushed out of the oven 16. The lower rails 11 are mounted on the ground G or on a supporting platform of concrete or other suitable material, and are engaged by spaced pairs of flanged wheels 24 mounted on axles 25 in brackets or trucks 26 upon which is mounted the lower structure 27 of the lower car 12. Uprights 28 lead to the upper structure 29 on which the rails 13 are mounted transversely to the rails 11.

The upper car 14 has a base 30 supported by flanged wheels 31 on axles 32 mounted in brackets or hangers 33 depending from the underside of the base 30. Mounted on the rearward end of the base 30 is a heavy counterweight 33a. Mounted on the upper side of the base 30 is a motor 34 which through a shaft 35 drives a reduction gear set 36, the output sprocket 37 of which drives an input or conveyor drive sprocket 38 by means of a conveyor chain 39. The sprocket 38 furnishes the power driving connection with an endless flight conveyor, generally designated 40, mounted within a tubular boom, generally designated 41, projecting forwardly from a feed hopper 42 mounted on the base 30 and receiving coal from a supply hopper 43. These portions, together with the counterweight 33a, are so mounted (Figure 1) on the upper car 14 as to counterbalance the weight of the boom 41, conveyor 40 and its load of coal.

The sprocket 38 is mounted on a shaft 46 which is journaled in the side wall of a housing 44 (Figure 2) and which is provided with elongated openings 45 to enable adjustment for taking up the slack in the endless conveyor 40. The slack takeup mechanism (not shown) is conventional. The tubular boom 41 near its junction with the feed hopper 42 is provided with a vent 47 for the discharge of hot gases which are carried back through the boom from the oven.

The conveyor 40 is supported at its rearward end on a sprocket 48 mounted on the shaft 46 and consists of a chain 49 having outer links 50 and inner links 51 (Figures 5, 6, 7 and 9) pivotally interconnected by pivot bolts 52. The outer links 50 are provided with arcuate edges 53 on one side thereof and the inner links 51 are provided with similar arcuate edges 54 and 55 on both sides thereof (Figure 6) so as to fit the concave periph-

ery 56 of a relatively small diameter pulley 57 at the forward end of the boom 41. The pulley 56 is rotatably mounted on bearings 58 (Figure 8) which in turn are mounted on an axle or stationary shaft 59, the ends of which are mounted in aligned bores 60 in side bars 61 and held in position by set screws 62 threaded therein as at 63. The bearings 58 are preferably high temperature bearings of the carbon type or of the graphite bronze type adapted to withstand the high temperatures occurring in the oven 16 and may be water-cooled for additional protection.

The rearward ends of the side bars 61 are notched as at 65 in their outer faces (Figure 5) so as to receive the forward portions 66 of the side walls 67 of the conveyor trough 68 (Figure 3) flush therewith. Pivotaly mounted as by the pivot bolts 69 on the inner links 51 of the chain 49 are the inner portions 70 of angle brackets 71 (Figures 6 and 7), the outer portions 72 of which are welded or otherwise secured to flight discs 73, the entire assembly forming flights, generally designated 74. The inner portions 70 are approximately triangular in shape and through one corner are provided with aligned bores 75 which are in turn aligned with a transverse bore 76 through each inner link 51. Inserted through the bores 75 and 76 are shear pins 77 having heads 78 on one end (Figure 9) and shanks 79 grooved as at 80 at the junctions between the angle bracket portions 70 and the sides of the links 51 in order to shear easily at these locations. The shear pins 77 are each provided with an external groove 81 in the projecting end of the shank 79 to receive a snap ring 82 or other fastener, such as a cotter pin or the like. The flight discs 73 are of irregular shape (Figure 7) with arcuate outer edges 83 and straight inner edges 84 joined by arcuate edge portions 85.

The arcuate edge portions 83 of the flight discs 73 are curved approximately to fit the cross-sectional curvature of the bottom 86 of the boom trough 68 (Figure 3), preferably with a slight clearance space therebetween, and the arcuate portions 85 are curved to approximately fit the interior of the conveyor boom conduit 67 (Figure 3) which is mounted between the upper edges 88 of the side portions 67 of the conveyor trough 68 so as to fill the opening therein, and secured thereto, as by welding, at that location. Thus, the endless conveyor 40 on its forward or lower course passes along the bottom portion of the conveyor trough 68 and on its return course enters the flared mouth 89 (Figure 6) of the conveyor conduit 87. In order to protect the forward end of the boom conveyor 41 as it is thrust into the interior of the oven, a guard cage 90 is provided. The guard cage 90 consists of a pair of approximately U-shaped rods 91 interconnected at intervals by cross rods 92 (Figures 5 and 6) and having their rearward upper and lower ends 93 and 94 welded or otherwise suitably secured to the outer walls of the conveyor conduit 87 and bottom portion 86 of the conveyor trough 68 respectively. The forward ends of the side bars 61 are also secured, as by welding, to the U-shaped rods 91.

At its rearward end, the tubular boom 41 consisting of the conveyor conduit 87 and trough 68 is secured to the edges of an opening 95 in the forwardly flared nose portion 96 of the feed hopper 42 (Figure 2). Extending from this opening 95 into the interior of the hopper 42 is a downwardly-inclined ramp 97 leading downward through an opening 98 in the rearward wall 99 of the hopper 42 to the rearward wall 100 of the housing 22, to the latter of which it is secured. An angle member 101 of inverted V-shaped cross-section (Figure 3) is supported at its forward end by a strut 102 depending from the conveyor conduit 87 and at its rearward end by the hopper wall 99 (Figure 2), and serves to hold the lower course of the conveyor down and to guide it upward along the ramp 97. The conveyor conduit 87 terminates at its rearward end 103 immediately adjacent the sprocket 48.

In order to regulate the amount of coal carried into the

boom or conveyor trough 68 by the conveyor flights 74, a regulating bar or gate 104 (Figures 2, 3 and 4) extends across the conveyor trough 68 at the rearward end thereof and is bolted as at 105 to the forward wall 106 of the feed hopper 42 (Figure 4). Additional holes 107 are provided in the front wall 106 arranged in a vertically-spaced relationship so as to permit the gate 104 to be placed at different heights in order to regulate the amount of coal which is permitted to enter the conveyor trough 68. The supply hopper 43 is roughly funnel-shaped and converges toward its junction 108 with the feed hopper 42.

Operation

In the operation of the invention, let it be assumed that there is a battery of ovens 16 mounted side by side in a row paralleling the lower tracks 11 and that the lower car 12 is wide enough and its upper tracks 13 long enough to permit the upper car 14 to move rearwardly a sufficient amount to withdraw the entire boom 41 and cage 99 from the oven 16. The lower car 12 is then moved along the tracks 11 to the elevator or other coal supply source, from which a measured quantity of coal, such as 15 tons, is deposited in the supply hopper 43 from which it passes downwardly into the feed hopper 42. Here it falls downward around the conveyor conduit 87 and over the hold-down member 101 onto the ramp 47. Assuming that the gate 104 has been set at the desired height according to the rate of coal feed desired, and also assuming that the motor 34 has been started in operation, the lower course of the conveyor 40 moves into the boom or conveyor trough 68, carrying with it the coal which constantly falls downward into the lower part of the feed hopper 42 from the supply hopper 43. At the same time, the coke oven feeding unit 15 has meanwhile been moved by means of the lower car 12 until it has arrived opposite the oven 16 which is to be charged, and the boom 41 is run into the interior of the combustion space 22 at the top of the oven 16 by moving the upper car 14 along the upper tracks 12.

Thus, a steady supply of coal is dumped out through the cage 90 at the forward end of the boom 41 as the boom makes its way into the interior of the oven 16. The rate of feed is so adjusted that when the cage 90 at the forward end of the boom 41 arrives at the rearward wall 20 of the oven 16, the conveyor 40 has deposited approximately half of the load of coal in the hoppers 42 and 43. The car 14 is then moved rearwardly along the upper tracks 12 away from the oven 16 while the conveyor 40 continues to dump the remaining half of the load of coal in the hoppers 42 and 43, the last of the charge being deposited as the forward end or cage 90 of the boom 41 reaches the opening 21 in the forward oven wall 19.

The charge of coal entering the boom 41 is, of course, comparatively cool and serves to cool the boom 41 and conveyor 40 to a certain extent. It also serves as a lubricant or as a bearing layer to hold the edges 83 of the flight discs 73 off the bottom 86 of the conveyor trough 68, thus reducing wear of the conveyor trough 68. The comparatively small diameter of the pulley 57, coupled with the curved edges 53 and 54 of the outer and inner links 52 and 55 cause these links to jump as they pass around the pulley 57, thereby causing the conveyor chain 49 to whip up and down. This action dislodges particles of coal which would otherwise tend to adhere to the conveyor 40. The carbon or bronze bearings 58 for the pulley 57 serve to journal the pulley 57 for free rotation even at the high temperatures encountered in the interior of the oven. Since the conveyor 40 fills the lower half of the oven 16 while it is going in and the upper half while it is coming out, the oven 16 is filled with its measured charge rapidly and efficiently without the need for any leveling off and without any spillage of coal. The depth of coal in the conveyor trough is preferably approximately twice the diameter of the flights 74. The con-

veyor trough 68 is, of course, open at its forward end to permit the coal to pour out through the cage 90.

If a foreign article or body, such as a piece of steel or hard rock, happens to enter the hopper 42 and encounters the conveyor 40, jamming of the conveyor is prevented by the shear pins 77 in the vicinity of the object or body. These give way at their fracture grooves 80 (Figure 9), permitting the flights 74 to pivot around their pivot bolts 69 and fold backward along the conveyor chain 49. Thus, the conveyor 40 is permitted to continue moving in its orbital path and thereby prevent from incurring damage due to the heat while the apparatus is removed from the oven 16 for removal of the obstruction and replacement of the shear pins. The arcuate portions 85 at the side edges of the conveyor flights engage the inner wall of the conveyor conduit 87 so as to keep the chain 49 off the inner wall and thereby prevent it from sawing its way through the conduit 87.

The boom conveyor apparatus 10 may also be employed to deliver materials from the supply hopper 43 to furnaces, kilns, chemical processing receptacles or to one or more of a series of vehicles or other material receivers located remote from the supply hopper 43 or separated therefrom by obstacles over which or through which the boom 41 may reach. One such arrangement occurs where there are several pairs of tracks side by side or a broad roadway or waterway where the oven 16 is located, the tracks or roadway being parallel to the tracks 11. With the boom conveyor apparatus 10, it is then possible to load any one or all of a series of railway cars, trucks, or vessels side by side on different tracks or in different rows on the roadway or waterway merely by first loading one car, truck or vessel, then moving over it to the next car, truck or vessel, and so on until the required number is filled. The supply hopper 43 may be elongated at its rearward side to permit continuous loading from a fixed overhead source, while it is moving back and forth.

If the cars, trucks or vessels are themselves conveniently movable past the apparatus 10, the lower car 12 and its rails 11 may be dispensed with and replaced by a platform structure 12 equipped with the rails 13. In the case of a waterway located where the oven 16 is located in Figure 1, the platform structure 12 may form a part of a dock structure, but the action of the boom conveyor apparatus 10 is similar to that already described in connection with the feeding of the coke oven 16 except that the apparatus 10 does not move transversely to the tracks 13. If, however, it is more convenient to move the boom conveyor unit 15 transversely to the axis of the boom 41 than to move the railway cars, trucks or vessels during the loading operations, this is done by means of the lower car 12 and rails 11 in the manner analogous to that previously described in loading the coke oven 16.

What I claim is:

1. A boom conveyor apparatus for conveying material to a plurality of stations disposed along a trackway, said apparatus comprising a car having wheels adapted to travel along said trackway, a guideway mounted on said car transversely of said trackway, a carriage reciprocably mounted on said guideway for motion therealong toward and away from each station as said car arrives opposite said last-mentioned station while traveling along said trackway, a material supply receptacle on said carriage, an elongated tubular self-sustaining boom structure supported at its rearward end only and having its rearward end fixedly mounted on said carriage and projecting outwardly therefrom, the outwardly-projecting portion of said tubular boom structure having substantially parallel upper and lower edges substantially throughout its entire length, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel

drivingly engaging said endless flexible member, said endless flexible member passing through a portion of said receptacle, flights mounted at spaced intervals along said endless flexible member, and a prime mover mounted on said carriage and drivingly connected to said rearward conveyor supporting wheel.

2. A boom conveyor unit for boom conveyor apparatus comprising a hollow tubular self-sustaining elongated boom structure adapted to be mounted at one end on said apparatus and project outwardly therefrom, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, said endless flexible member passing through said hollow tubular boom structure, and flights mounted at spaced intervals along said endless flexible member, said hollow boom structure including a lower conduit portion of approximately U-shaped cross-section traversed by the forwardly moving portion of said endless flexible member and an upper conduit portion of substantially circular cross-section traversed by the rearwardly moving portion of said endless flexible member.

3. A boom conveyor unit for boom conveyor apparatus comprising a hollow tubular self-sustaining elongated boom structure adapted to be mounted at one end on said apparatus and project outwardly therefrom, a forward conveyor supporting element rotatably mounted at the forward end of said boom structure, a rearward conveyor supporting element rotatably mounted behind the rearward end of said boom structure, an endless flexible member trained between and around said conveyor supporting wheels, said rearward supporting wheel drivingly engaging said endless flexible member, said endless flexible member passing through said hollow tubular boom structure, and flights mounted at spaced intervals along said endless flexible member, said hollow boom structure including a lower conduit portion of approximately U-shaped cross section traversed by the forwardly moving portion of said endless flexible member and an upper conduit portion of substantially circular cross-section traversed by the rearwardly moving portion of said endless flexible member, the side walls of said lower conduit portion extending upwardly into engagement with and secured to said upper conduit portion.

4. A boom conveyor unit for boom conveyor apparatus comprising an elongated boom structure, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, and flights mounted at spaced intervals along said endless flexible member, said flights being pivotally connected to said endless flexible member and foldable rearwardly therealong, said flights also having frangible shear elements normally engaging and locking said flights against such folding motion relatively to said endless flexible member, said shear elements being rupturable to release said flights to fold rearwardly in response to the exertion thereon of a predetermined excessive force.

5. A boom conveyor unit for boom conveyor apparatus comprising an elongated boom structure, a forward conveyor supporting wheel rotatably mounted at the forward end of said boom structure, a toothed rearward conveyor supporting and driving wheel rotatably mounted behind the rearward end of said boom structure, an endless flexible member trained between and around said conveyor supporting elements and drivingly engaging said rearward supporting wheel drivingly engaging said endless

flexible member, and flights mounted at spaced intervals along said endless flexible member, said endless flexible member comprising an endless chain having links with arcuate edge portions matingly engageable with the periphery of said forward conveyor supporting wheel.

6. A boom conveyor unit for boom conveyor apparatus comprising a hollow tubular elongated boom structure adapted to be mounted at one end on said apparatus and project outwardly therefrom, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, said endless flexible member passing through said hollow tubular boom structure, and flights mounted at spaced intervals along said endless flexible member, said forward supporting wheel being mounted externally and forwardly of the forward end of said hollow boom structure, and a forwardly-converging material-deflecting and shielding structure mounted around the forward side of said forward supporting wheel.

7. A boom conveyor unit for boom conveyor apparatus comprising a hollow tubular elongated boom structure adapted to be mounted at one end on said apparatus and project outwardly therefrom, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, said endless flexible member passing through said hollow tubular boom structure, and flights mounted at spaced intervals along said endless flexible member, said forward supporting wheel being mounted externally and forwardly of the forward end of said hollow boom structure, and a forwardly-converging material-deflecting and shielding structure of open cage construction mounted around the forward side of said forward supporting wheel.

8. A boom conveyor unit for boom conveyor apparatus comprising an elongated boom structure, a heat-resisting bearing unit mounted at the forward end of said boom structure, a forward conveyor supporting wheel rotatably mounted on said bearing unit, a rearward conveyor supporting wheel rotatably mounted behind the rearward end of said boom structure, an endless flexible member trained between and around said conveyor supporting wheels, said rearward supporting wheel drivingly engaging said endless flexible member, and flights mounted at spaced intervals along said endless flexible member.

9. A boom conveyor unit for boom conveyor apparatus comprising a hollow tubular elongated boom structure, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, said endless flexible member passing through said hollow tubular boom structure, flights mounted at spaced intervals along said endless flexible member, and a material flow volume regulating member disposed at the entrance to said boom structure, said flow regulating member extending at least partially across and partially obstructing said entrance.

10. A boom conveyor unit for boom conveyor apparatus comprising a hollow tubular elongated boom structure, a forward conveyor supporting wheel rotatably mounted at the forward end of said boom structure, a rearward conveyor supporting wheel rotatably mounted behind the rearward end of said boom structure, an end less flexible member trained between and around said

conveyor supporting wheels, said rearward supporting wheel drivingly engaging said endless flexible member, said endless flexible member passing through said hollow tubular boom structure, flights mounted at spaced intervals along said endless flexible member, and a material flow volume regulating member disposed at the entrance to said boom structure and adjustably mounted thereon for adjustment toward and away from said flights, said flow regulating member extending at least partially across and partially obstructing said entrance.

11. A boom conveyor apparatus comprising a material supply receptacle, an elongated boom structure connected to said receptacle and projecting outwardly therefrom, said receptacle having an exit opening at its junction with said boom structure, a forward conveyor supporting wheel rotatably mounted at the forward end of said boom structure, a rearward conveyor supporting wheel rotatably mounted behind the rearward end of said boom structure, an endless flexible member trained between and around said conveyor supporting wheels, said rearward supporting wheel drivingly engaging said endless flexible member, said endless flexible member passing through a portion of said receptacle, flights mounted at spaced intervals along said endless flexible member, said material recep-

tacle having a bottom wall inclined upwardly toward said exit opening, and an upwardly-inclined elongated conveyor holdown member disposed above said bottom wall in spaced relationship therewith and guidingly engageable with said endless flexible member.
